Stafford, England, assignors to The English
Electric Company Limited, London, England, a
British company

Application December 19, 1949, Serial No. 133,884
In Great Britain December 31, 1948

3 Claims. (Cl. 250—27)

1

This invention relates to electrical pulse generating circuits.

An object of the invention is to provide a pulse generating circuit suitable to serve as a radar modulator and to handle pulse powers up to the order of 10 megawatts and more.

In carrying the invention into effect, a pulse-forming network is charged through a step-up transformer from a source of alternating current having frequency equal to that of the pulse-repetition required, and is discharged by a pulse of very heavy current through a load and through a discharge tube of the mercury pool type. This discharge is immediately preceded by another heavy current discharge through the tube.

Fig. 1 of the accompanying drawing illustrates diagrammatically a pulse generating circuit which embodies the invention in preferred form. This circuit is employed as pulse modulator in a radar transmitter. Fig. 2 illustrates the wave forms at various points in the circuit of Fig. 1.

The network 10 is a pulse-forming network which is alternately charged, relatively slowly, from an alternating current generator 12 and discharged, very rapidly, through a load 13.

The frequency of the alternating current generated by generator 12 is equal to the repetition frequency required for the pulses, which may be about 500 cycles per second. At this frequency, network 10 presents impedance which is substantially a capacitance. It is charged from generator 12, during part of a cycle thereof, through a step-up transformer 11 and a choke 26, and it reaches a potential of about 20 kilovolts.

The discharge path for the network 10 comprises in series the load 13, represented as a resistance, and the arc path from anode 14 to cathode 15 of a mercury pool discharge device. The discharge of the network 10 takes the form of a square-wave pulse of very heavy current, say about 500 amps., subsisting for about one or two microseconds.

The mercury pool discharge device is provided with an igniter 16 supplied with current from a direct current source 27 of about 100 volts, this current being under control of a push-button 17 and limited by series resistor 28.

The direct current source 27 also supplies current through choke 29 and resistor 31 to an excitation anode 18. This current is limited by resistor 31 to about 5 amps., and maintains a steady excitation arc from anode 18 to cathode 55

2

15 after the igniter has been operated by push-button 17.

In order to avoid the danger that the excitation arc may be quenched when network 10 is discharged, a further anode 19 is arranged to discharge a condenser 20 during the period covering the instant when discharge of network 10 is to occur.

Condenser 20 is charged substantially linearly 10 from a direct current source 21 through a large inductance 22. Once in every cycle of alternating source 12, condenser 20 is discharged by a heavy current flowing through inductance 23 and the path between anode 19 and cathode 15. The 15 discharge is initiated, about 50 microseconds in advance of the instant for discharge of network 10, by application of a firing pulse to control grid 24 which covers anode 19. Inductance 23 and condenser 20 are so proportioned that the discharge current will have the form of a half sine wave of duration about 100 microseconds and peak value about 150 amps. About the instant when this current reaches its peak, a firing pulse is applied to control grid 25 which covers anode 25 14, and the very rapid discharge of capacitance 10 through load 13 then occurs.

The firing pulses for the control grid 24 are derived from a small alternating current generator 30 which is coupled to generator 12 and produces alternating current of the same frequency. The output of generator 30 is applied through a phase shifter 31 to a pulse generator 32, from which firing pulses are applied over bias source 33 to control grid 24. Phase shifter 31 can 35 be adjusted so that these firing pulses occur when network 10 is charged and ready for discharge.

The firing pulses for the control grid 25 are applied from a pulse generator 34 over bias source 35. Pulse generator 34 is controlled from pulse generator 32 through time delay network 36, which can be adjusted to give the desired interval between the firing pulses on control grids 24 and 25.

In Fig. 2—

45 Wave form V12 represents the 500 cycles per second sine wave voltage generated by the generator 12 of Fig. 1.

Wave form V24 represents the voltage of control grid 24 relative to cathode 15.

50 Wave form V20 represents the voltage across condenser 20.

Wave form 119 represents the intermittent half sine wave discharge currents from anode 19. The time scale is exaggerated relative to that of wave forms V12, V24, V20, because the duration

of each of these discharges from anode 19 is only about 100 microseconds.

Wave form V25 represents the voltage of control grid 25 relative to cathode 15.

Wave form V14 represents the voltage between anode 14 and cathode 15.

Wave form I13 represents the current pulses through load 13; and as each of these has a duration of only about two microseconds, the time scale is exaggerated even more than that of wave form I19.

In the method of operating the apparatus which has been described, the discharge between anode 14 and cathode 15 is timed to occur when that between anode 19 and cathode 15 is near its peak. Alternatively, however, the discharge between anode 14 and cathode 15 may be timed to occur at any time up to 100 microseconds later than this.

What we claim as our invention and desire to secure by Letters Patent is:

1. An electrical pulse generating circuit comprising an electric discharge tube having a mercury pool cathode, a first anode provided with a first control grid, and a second anode provided with a second control grid; a load, a first capacitance, a path for discharging said first capacitance through said load and through the arc path between said first anode and said cathode by a very heavy current subsisting for a period of the order of microseconds upon the application of a firing pulse to said first control grid; an alternating current source and a step-up transformer arranged to charge said first capacitance; a second capacitance connected in series

with an inductance between said second anode and said cathode, means to charge said second capacitance, means to provide an excitation arc in the tube, and means synchronized with said alternating current source to apply a firing pulse to said second control grid; said inductance and said second capacitance being so proportioned that the heavy current discharge which then flows between said second anode and said cathode forms a substantially sinusoidal half-wave subsisting for a period of the order of hundreds of microseconds, and means to apply a firing pulse to said first control grid at a time within a period of 100 microseconds commencing during said heavy current discharge.

2. A circuit according to claim 1, wherein the electric discharge tube is provided with means to maintain a continuous excitation arc therein.

3. A circuit according to claim 2, wherein the electric discharge device is provided with an igniter for initiating the excitation arc.

JOHN MCINTYRE FERGUSON.
